UNITED STATES PATENT OFFICE.

MICHAEL M. CROWLEY, OF SIOUX CITY, IOWA.

LOCOMOTIVE BOILER.

Application filed March 4, 1927. Serial No. 172,640.

My invention relates to locomotive boilers and has for its object primarily the increase of water circulation in the heated zone to produce quicker and more efficient 5 steaming facility.

The above object is attained by a new firebox construction wherein a much greater surface of water carrying chambers is presented to the flames and heated gases of 10 combustion than in any existing type of locomotive firebox. The area of brick arch, an inert body, incapable of transmitting heat into power, is reduced to a minimum without sacrificing the necessary accessibility 15 of the boiler flue sheet to the workman.

A further object of my invention is to provide such a firebox construction having the water circulatory quality mentioned, in 20 which the possibility of crystallization of the metal walls of the firebox is minimized.

A still further object of my invention is to obtain a separated draft within the firebox such that there is less possibility of the air currents concentrating, such as may happen 25 in the ordinary firebox where a burned-through spot appears in the coal bed of the fire.

Another object of the invention is to provide firebox construction of very sturdy 30 character, such as to resist the combined forces of steam pressure and vibration, as well as the force of coal thrown against its walls during the firing process.

A further object of the invention is to 35 construct the firebox so as to give the greatest accessibility to the flue sheet with a minimum area of removable brick arch.

With these and other objects in view, my 40 invention consists in the construction, arrangement and combination of the various parts of my device, whereby the objects contemplated are attained, as hereinafter more fully set forth, pointed out in my claims, and illustrated in the accompanying drawings, in which:

Fig. 1 is a longitudinal, central, vertical, sectional view through a locomotive firebox embodying my invention.

Fig. 2 is a transverse, sectional view 50 through the same, and

Fig. 3 is a horizontal, sectional view through the same.

The solution of the problem of increasing 55 water circulation in the heated area of a locomotive boiler, involves generally the providing of relatively narrow water boxes,

formed of pairs of substantially parallel walls stay-bolted together, within the firebox, and connected to the boiler so as to secure circulation of water through the firebox proper, as well as around it. 60

However, this involves further problems. The boxes must be so arranged as to promote the circulation of the water in its natural channels; for instance, the colder water 65 always settles to the bottom of the boiler and should be drawn from there and thence distributed rearwardly as far as possible and allowed to return to the boiler in directions which will not retard the normal 70 flow of water at the places where the water is discharged, back into the boiler.

To obtain the maximum benefit from the fire, the boxes should be located horizontally, yet I find that it is utterly impossible 75 to locate a flat water box, of the proper narrowness, within a firebox, where its upper wall is in a horizontal position, without hindering the escape of steam bubbles. In any arrangement wherein the upper wall of a 80 water circulating box located in the midst of the flames and subjected on both sides to their action, does hinder the escape of steam bubbles, crystallization of the metal walls will occur. It will be understood in this 85 connection that crystallization is a transforming of the metal in the walls to a more brittle and weaker condition, due to overheating. It will be understood in this connection that the formation of steam is so

rapid at the surfaces directly exposed to the flame, that unless there is a direct upward outlet for the steam over the entire area of the water box, the particular portion where escape of the steam is restricted, will not 90 have a sufficient supply of water to keep the metal walls of the box properly cooled. The result is crystallization and burning out of 95 the box. For instance, if a horizontal, flat box communicates at one side with the leg of a locomotive, and must receive its circulation

from the leg, it will be impossible for the water to rush in fast enough to displace the steam which is attempting to force itself 100 out and thereby resisting the attempt of the water to enter. Furthermore, steam is being 105 rapidly formed in the leg itself, and consequently the natural upward circulation of water within the leg will oppose the circulation laterally into the water box.

I therefore construct the firebox so that 110 the water box receives water at its lower

end from the throat of the boiler where the water is coldest, and thence offers a free passage both upwardly and laterally, for the heated water and steam, the greater percentage of steam rising directly, in a vertical passage, to the crown of the boiler, and the remainder being offered an escape in a lateral, upwardly inclined direction, flowing into the leg of the boiler in a direction such as to stimulate the normal upward circulation of water within the leg.

The usual locomotive boiler is shown in the drawings, including the top sheet 10, crown sheet 11, boiler head 12, flue sheet 13, flues 14, inner throat sheet 15, outer throat sheet 16, firebox back sheet 17, and inner and outer side sheets 18 and 19 respectively, forming the boiler crown 20, legs 21 and belly 22.

20 My invention provides the water boxes 23 and 24, the former comprising upper walls 25 and lower walls 26, secured to the inner side sheets 18 on either side of openings 27 therein. The boxes 24 comprise inner walls 28 and outer walls 29, secured at one end to the crown sheet on either side of openings 30, and at their other ends to the walls 25 of the boxes 23, on either side of openings 31 in the latter boxes.

30 The openings 27 in the inner side sheets extend into the flue sheet, and the boxes 23 are connected to the belly of the boiler their full width at their forward ends; thus giving a maximum area of water entrance. Water 35 will enter the boxes only at the forward ends, due to the inclination of the boxes 23 outwardly and upwardly approximately as shown in Fig. 2. This inclination causes the heated water in the boxes to flow toward the 40 legs during practically the entire length of the boxes 23. In thus discharging upwardly directed water currents into the legs of the boiler, the boxes 23 will accelerate the natural flow of water in the legs, which is upward.

45 Most of the water entering a box 23 will enter from the throat sheet opening. However, there is no definite limit to the size of the water entrance. It will be understood that where necessary to balance the intake against the outflow, water may enter from the sides. Due to the fact that the entire body of water flowing through a box 23 has a general rearward direction, the discharge 50 current will be stronger at the rear than at the forward end and consequently, any water thus entering from the sides will enter at the forward end. Thus there will, at all times, be a definite division point in the opening 27, around which the incoming and outflowing currents will revolve, and there will be no tendency for these currents to oppose each other.

55 Due to the fact that the upward inclination of the boxes 23 tends to discharge the

flow of water into the boxes from the sides, the greatest volume will be taken in at the forward ends, as already stated, and the flow of water at these ends will therefore be very rapid, very materially stimulating the natural flow of water rearwardly in the belly of the boiler. On the other hand, since the intake openings are in no way definitely constricted, there will be no possibility of an insufficient supply of water to the boxes 70 75 23 under any circumstances, and consequently, no danger of burning out or crystallization.

The danger of crystallization is further eliminated by the arrangement of the water boxes so that at their inner sides, where the greatest steaming will occur, there is a direct upward exit for the steam, thus further stimulating the circulation of water within the boxes 23, increasing the draft at the intake end, and, most important, making it impossible for steam to collect within the boxes 23 at their inner sides. The escape of steam from the remainder of the boxes is assured by the upward inclination of the upper walls 90 95 25. It will be noted that at no point can the steam become trapped beneath a horizontal surface. In this connection, it may be noted that the region most susceptible to burning would be the rear ends of the boxes 23, as at 35, where the water can no longer flow rearwardly. However, the upward inclination of the rear ends of the boxes will enable the steam formed at the ends of the boxes to escape rapidly enough, and since this escape of steam is not in such a direction as to oppose the incoming stream of water, moving rearwardly, there is little possibility of even these regions becoming filled with steam.

100 In conclusion, it may be stated that crystallization is effectively opposed by, first, creating a general rearward current of water in the water boxes 23, second, making the intake opening unrestricted in area, third, inclining the boxes upwardly to the legs of the boiler to cause the currents to flow laterally as well as rearwardly, and, fourth, providing a direct upward outlet for the steam at the inner sides of boxes which are in the hottest zone of the fire boxes.

105 The walls of the boxes 23 and 24 are stay-bolted together as shown and may be secured to the usual walls of the fire box in any approved manner such as by welding and riveting.

110 The boxes 23 form the greater majority of the inclined arch usually constructed of inert fire brick. The space between the boxes 23 serves a double purpose. In the first place, by eliminating any connection between the two boxes 23, it prevents the formation of a neutral zone in which the water currents would separate and thereby allow the formation of unescaped steam, and second, it provides an opening through which the work-

man may gain access to the flue sheet. This opening is made only wide enough to admit the body of a workman and, the boxes being at the sides of the fire box, only one opening 5 is used.

The water boxes 23 serve not only to replace the usual brick arch, but also as water circulating and steaming means as hereinbefore described.

10 The fire brick are indicated at 36.

The boxes 23 and 24 form between them individual flue spaces 37 and the boxes 24 form a central flue space 38. Thus the flame from the grate is divided into three separate 15 channels and should a thin spot occur at any region of the bed of coals and thereby allow excess air to pass through the grate at one spot, the division of the draft to three separate channels pulling upon three different 20 regions of the grate will tend to eliminate the possibility of the draft being concentrated at the weak spot in the fire bed.

Some changes may be made in the construction and arrangement of the parts of 25 my invention without departing from the real spirit and purpose of my invention, and it is my intention to cover by my claims, any modified forms of structure or use of mechanical equivalents, which may be reasonably included within their scope.

I claim as my invention:

1. In a locomotive boiler having a crown, belly, and legs, a pair of water boxes connected, at their forward ends, to the belly, 35 and, at their sides, to the legs, said water boxes being spaced apart and inclined rearwardly, upwardly, and laterally away from the center of the fire-box, and a pair of vertically disposed longitudinally extending 40 imperforate water channels connecting the inner sides of the boxes with the space above the crown.

2. In a locomotive boiler having a crown, belly, and legs, a pair of water boxes connected at their forward ends to the belly, 45 and at their sides to the legs, said forward and side connections being continuous, said water boxes being spaced apart and inclined rearwardly, upwardly, and laterally away from the center of the fire-box, and a pair of vertically disposed longitudinally extending, imperforate water channels connecting the inner sides of the boxes with the space above the crown.

55 3. In a locomotive boiler having a crown belly, and legs, a pair of water boxes connected at their forward ends to the belly, said connections extending substantially entirely the full width of the boxes, and, said 60 boxes being connected at their sides to the legs, said water boxes being spaced apart and inclined rearwardly, upwardly, and laterally away from the center of the fire-box, and a pair of vertically disposed longitudinally extending imperforate water chan-

nels connecting the inner sides of the boxes with the space above the crown.

4. In a locomotive boiler having a crown, belly, and legs, a pair of water boxes connected at their forward ends to the belly, 70 and at their sides to the legs, said water boxes being spaced apart and inclined rearwardly, upwardly and laterally away from the center of the fire box, a pair of vertically disposed longitudinally extending imperforate water channels connecting the inner sides of the boxes with the space above the crown and a brick arch supported between the spaced sides of the boxes.

5. In a locomotive boiler having a crown, 80 belly, and legs, a pair of water boxes connected at their forward ends to the belly, and at their sides to the legs, said water boxes being spaced apart and inclined rearwardly, upwardly, and laterally away from the center of the fire box, a pair of vertically disposed longitudinally extending imperforate water channels connecting the inner sides of the boxes with the space above the crown and a brick arch supported between 85 the spaced sides of the boxes, said channels extending substantially the full length of the boxes, thereby forming three separated draft flues.

6. In a locomotive boiler having a crown, 90 belly and legs, a pair of water boxes, connected at their forward extremities to the belly and at their sides to the legs, said water boxes being spaced apart laterally and inclined rearwardly, upwardly and laterally away from the center of the fire box, the lowest extremities of said water boxes being at their adjacent sides and a pair of vertically disposed longitudinally extending imperforate water channels connecting said 95 lower extremities of the boxes with the space above the crown.

7. In a locomotive boiler having a crown, 100 belly, and legs, a pair of water boxes connected at their forward ends to the belly, and at their sides to the legs, said water boxes being spaced apart and inclined rearwardly, upwardly, and laterally away from the center of the fire box, and a pair of vertically disposed longitudinally extending imperforate water channels connecting the lower extremities of the boxes with the space above the crown, the water boxes extending toward each other beyond said channels to form projecting ledges and a brick arch closing the space between said water boxes supported upon said ledges and retained against lateral movement by said vertical channels.

8. In a locomotive boiler having a crown, 110 belly, and legs, a pair of water boxes connected at their forward ends to the belly, and at their sides to the legs, said forward and side connections being continuous, said water boxes being spaced apart and inclined 115 rearwardly, upwardly, and laterally away from the center of the fire box, and a pair of vertically disposed longitudinally extending imperforate water channels connecting the inner sides of the boxes with the space above the crown.

from the center of the fire box, and a pair of vertically disposed longitudinally extending imperforate water channels connecting the inner sides of the boxes with the space above the crown, the vertical water channels serving to support the inner extremities of the water boxes.

9. In a locomotive boiler having a crown, belly, and legs, a pair of water boxes connected at their forward ends to the belly, and at their sides to the legs, said water boxes being spaced apart and inclined rearwardly, upwardly, and laterally away from the center of the fire box, and a pair of ver-

tically disposed longitudinally extending imperforate water channels connecting the lower extremities of the boxes with the space above the crown, the upper walls of the water boxes from the vertical water channels to the crown sheet offering unobstructed upwardly inclined surfaces, against which rising currents may freely flow to the crown without being trapped at any point.

Signed this 21st day of February, 1927,
in the county of Woodbury and State of Iowa.

MICHAEL M. CROWLEY.
